SLIDING MEMBER FOR PUMP AND PUMP OPERATION STATE DETECTION SYSTEM

This application is the U.S. National Phase of International Application No. PCT/JP2014/068470 filed on Jul. 10, 2014, entitled “*Sliding Member for Pump and Pump Operation State Detection System*” and claims priority to Japanese Patent Application No. 2013-170244, filed on Aug. 20, 2013, which are hereby expressly incorporated by reference in their entirety for all purposes.

TECHNICAL FIELD

The present invention generally relates to a sliding member and, but not by way of limitation, to a sliding member for pumps, which is used as a pump, and to a pump operation state detection system capable of detecting wear of the sliding member caused in the pump.

BACKGROUND ART

Hitherto, there has been provided a pump such as a uniaxial eccentric screw pump as disclosed in Patent Literature 1 (JP 2008-175199 A). The uniaxial eccentric screw pump is capable of force-feeding a fluid having a high viscosity, such as starch syrup, a fluid that is prone to alteration and is required to be handled carefully, a fluid containing a solid, fibers, air bubbles, as well as a fluid having a low viscosity, such as a liquid. Therefore, the uniaxial eccentric screw pump can also be used suitably for force-feeding food and the like.

Here, the above-mentioned uniaxial eccentric screw pump exerts a pump action through rotation of a male-screw-shaped rotor in a stator having a female-screw-shaped insertion hole. Further, as in the case of the stator in the uniaxial eccentric screw pump, a sliding member configured to slide while being in contact with another member (rotor in the uniaxial eccentric screw pump) along with operation of the pump may be arranged so as to be exposed to a flow path through which a fluid to be force-fed flows. Therefore, when a pump such as a uniaxial eccentric screw pump is used in an unintended usage form to apply an excessive load to the stator and the rotor, there is a risk in that a wear substance and a flake of the sliding member may be generated and mixed in the fluid.

Therefore, there is a demand for providing a sliding member for pump in which even the use of the sliding member in such a state that a wear substance and the like are generated, as described above, can be quickly and accurately grasped, and for providing a pump operation state detection system including the sliding member. In particular, in a pump capable of force-feeding food and the like as in the above-mentioned uniaxial eccentric screw pump, there is a strong demand for quickly and accurately detecting the mixing of a wear substance and the like in the fluid.

In view of the foregoing, it is an object of the present invention to provide a sliding member in which generation of a wear substance and the like can be quickly and accurately grasped even if the wear substance and the like are generated when the sliding member slides while being in contact with another member, and to provide a pump operation state detection system for a pump using the sliding member.

SUMMARY OF THE INVENTION

In order to solve the above-mentioned problem, according to an embodiment of the present invention, there is provided

a sliding member for pumps, which is arranged so as to be exposed to a flow path of a fluid in the pump, and is configured to slide while being in contact with another member along with operation of the pump. The sliding member may include a resin or a rubber, and 10% to 30% of metal powder in terms of a weight ratio.

In this embodiment, the sliding member is made of a resin or a rubber and contains 10% to 30% of metal powder in terms of a weight ratio. With such configuration, even if a wear substance and a flake of the sliding member are generated and mixed in the fluid flowing through the flow path due to the use of the sliding member in an unintended usage form and the like, the mixing of a wear substance can be quickly and accurately detected through the use of a detection device capable of detecting the presence of the metal powder, as typified by a metal detector and an X-ray foreign matter inspection machine.

The above-mentioned sliding member according to the embodiments of the present invention may be suitably used as a stator in a uniaxial eccentric screw pump. The uniaxial eccentric screw pump may include a rotor which is formed into a male screw shape and is configured to receive power to eccentrically rotate. The stator may have an inner peripheral surface formed into a female screw shape and having the flow path formed in the stator.

As described above, the stator of the uniaxial eccentric screw pump is a sliding member in which the rotor formed into a male screw shape and is inserted so as to eccentrically rotate and be exposed to the flow path formed therein. Therefore, according to the one embodiment of the present invention, even when a wear substance and a flake of the stator serving as the sliding member in the uniaxial eccentric screw pump are generated and mixed in the fluid to be force-fed, the presence/absence of the mixing of a wear substance and a flake can be quickly and accurately detected through detection of the location of the metal powder by a detection device such as a metal detector and an X-ray foreign matter inspection machine.

In the above-mentioned sliding member according to a preferred embodiment of the present invention, the stator may have a tapered end surface on a discharge side and/or a suction side of the fluid in the stator.

With such configuration, cracks can be prevented from being formed by the influence of a discharge pressure or a suction pressure on the end surface on the discharge side and/or the suction side of the stator.

According to the preferred embodiment of the present invention, in the above-mentioned sliding member, the resin or the rubber may have a constant thickness.

Even in the case of such configuration, through use of the detection device capable of detecting the presence of the metal powder, the mixing of a wear substance containing the metal powder can be quickly and accurately detected.

Here, in the above-mentioned sliding member, it is considered that there is a high risk in that a wear substance and a flake are generated and mixed in the fluid in the vicinity of a sliding surface configured to slide while being in contact with another member, and there is a low risk in that a wear substance and the like are generated in a region away from the sliding surface.

Based on such findings, the sliding member according to the embodiments of the present invention, may have a sliding surface configured to slide while being in contact with another member, and a content of the metal powder is higher in a region on the sliding surface side than in other regions.

With such configuration, the other regions excluding the region on the sliding surface side is allowed to contain a small amount of the metal powder and not to be broken easily while the mixing of a wear substance and the like can be detected through the use of the detection device capable of detecting the presence of the metal powder. Further, with the above-mentioned configuration, the region on the sliding surface side and the other regions may be formed of different materials.

In yet another embodiment, there is provided a pump operation state detection system that includes: a pump having the above-mentioned sliding member; a detection device capable of detecting presence of metal powder contained in the fluid discharged from the pump; and a control device capable of determining that a wear substance generated along with wear of the stator is mixed in the fluid discharged from the pump under a condition that the detection device detects the presence of the metal powder.

In the pump operation state detection system according to the embodiments of the present invention, the sliding member containing 10% to 30% of metal powder in terms of a weight ratio is used. Further, in the pump operation state detection system, the detection device capable of detecting the presence of the metal powder, as typified by a metal detector and an X-ray foreign matter inspection machine, is arranged in at least a part of a conveyance path through which the fluid is conveyed. With this, it can be quickly and accurately detected whether or not a wear substance and the like are mixed in the fluid under the condition that the detection device detects the metal powder.

Thus, according to the embodiments of the present invention, it becomes possible to provide a sliding member in which the generation of a wear substance and the like can be quickly and accurately grasped even if the wear substance and the like are generated when the sliding member slides while being in contact with another member. And also, it becomes possible to provide the pump operation state detection system for a pump using said sliding member.

BRIEF DESCRIPTION OF THE DRAWINGS

The present disclosure is described in conjunction with the appended figures:

FIG. 1 is a configuration view for illustrating a pump operation state detection system according to one embodiment of the present invention.

FIG. 2 is a cross-sectional view of a uniaxial eccentric screw pump arranged in the pump operation state detection system illustrated in FIG. 1.

FIG. 3 is a flowchart for illustrating an example of operation of the pump operation state detection system illustrated in FIG. 1.

FIG. 4 is a cross-sectional view for illustrating a stator according to a modified example.

FIG. 5 is a cross-sectional view for illustrating a stator according to a modified example.

FIG. 6 is a graph for showing experimental data according to Example 1.

DETAILED DESCRIPTION OF THE INVENTION

The ensuing description provides preferred exemplary embodiment(s) only, and is not intended to limit the scope, applicability or configuration of the disclosure. Rather, the ensuing description of the preferred exemplary embodiment(s) will provide those skilled in the art with an enabling

description for implementing a preferred exemplary embodiment(s) of the disclosure. It should be understood that various changes may be made in the function and arrangement of elements without departing from the spirit and scope of the invention as set forth in the appended claims.

In what follows, an embodiment in which a sliding member for a pump and a pump operation state detection system of the present invention are applied will be described. A pump operation state detection system 10 described in this embodiment is configured to detect an operation state of the pump, more specifically, whether or not a wear substance and a flake of the sliding member for pump, which is arranged in the pump, are generated, to thereby determine the presence/absence of abnormality.

Referring first to FIG. 1, an exemplary embodiment of the pump operation state detection system 10 is shown. The pump operation state detection system 10 may include a uniaxial eccentric screw pump 20 as the pump, and can detect a wear substance and the like by a detection device 100 and determine the presence/absence of operation abnormality by a control device 120. More specifically, the pump operation state detection system 10 has features and operation controls of a stator 50 serving as the sliding member for pump, a detection device 100, and a control device 120. Prior to description of the detailed configurations and operation controls of the stator 50, first an overview of the configuration of the uniaxial eccentric screw pump 20 is described.

<<Schematic Configuration of Uniaxial Eccentric Screw Pump 20>>

FIG. 2 illustrates an embodiment of the uniaxial eccentric screw pump 20, a so-called rotary displacement pump, in detail. As shown in this figure, the uniaxial eccentric screw pump 20 may include a uniaxial eccentric screw pump mechanism 30 as its main component. As illustrated in FIG. 2, the stator 50, a rotor 60, and a power transmission mechanism 70 are accommodated in a casing 40. The casing 40 is a tubular member made of a metal, and has a first opening 42 formed at one end in a longitudinal direction. Further, a second opening 44 is formed in an outer peripheral portion of the casing 40. The second opening 44 communicates to an internal space of the casing 40 in an intermediate part 46 positioned in an intermediate portion in the longitudinal direction of the casing 40.

The first opening 42 and the second opening 44 respectively serve as a suction port and a discharge port of the pump mechanism 30. In the uniaxial eccentric screw pump 20, when the rotor 60 is rotated in a forward direction, the first opening 42 is allowed to serve as the discharge port, and the second opening 44 is allowed to serve as the suction port. Further, when the rotor 60 is rotated in a backward direction, the first opening 42 is allowed to serve as the suction port, and the second opening 44 is allowed to serve as the discharge port.

The stator 50 is a member having a substantially cylindrical external appearance formed of a material containing an elastic body such as a rubber or a resin as a main component. An inner peripheral surface 52 of the stator 50 is a member formed into an (n+1)-thread (n=1 in this embodiment) female screw shape. Further, a through hole 54 of the stator 50 is formed so that a cross-sectional shape (opening shape) thereof becomes a substantially oval shape in sectional view at any position in the longitudinal direction of the stator 50. Further, the stator 50 is tapered in both end portions on the discharge side and the suction side of the uniaxial eccentric screw pump 20.

The rotor **60** is a shaft body made of a metal formed into an n-thread (n=1 in this embodiment) male screw shape. The rotor **60** is formed so that a sectional shape thereof becomes a substantially true circular shape in sectional view at any position in the longitudinal direction. The rotor **60** is inserted into the through hole **54** formed in the above-mentioned stator **50**, thereby being capable of eccentrically rotating freely in the through hole **54**.

When the rotor **60** is inserted into the stator **50**, an outer peripheral wall **62** of the rotor **60** and the inner peripheral surface **52** of the stator **50** are brought into close contact with each other at each tangent therebetween, and a fluid conveyance path **56** (cavity) is formed between the inner peripheral surface **52** of the stator **50** and the outer peripheral wall of the rotor **60**. The fluid conveyance path **56** extends in a helical fashion in the longitudinal direction of the stator **50** and the rotor **60**.

When the rotor **60** is rotated in the through hole **54** of the stator **50**, the fluid conveyance path **56** advances in the longitudinal direction of the stator **50** while rotating in the stator **50**. Therefore, when the rotor **60** is rotated, a fluid is sucked into the fluid conveyance path **56** from one end of the stator **50** and is transferred to the other end of the stator **50** in a state of being confined in the fluid conveyance path **56**. Thus, the fluid can be discharged at the other end of the stator **50**. The pump mechanism **30** according to this embodiment is used by rotating the rotor **60** in the forward direction, and can force-feed a viscous liquid sucked from the second opening **44** so that the liquid is discharged from the first opening **42**.

The power transmission mechanism **70** is configured to transmit power from a driver **80** to the above-mentioned rotor **60**. The power transmission mechanism **70** includes a power transmission part **72** and an eccentric rotation part **74**. The power transmission part **72** is arranged at one end in the longitudinal direction of the casing **40**. Further, the eccentric rotation part **74** is arranged in the intermediate part **46** formed between the power transmission part **72** and a stator mounting part **48**. The eccentric rotation part **74** is a part connecting the power transmission part **72** and the rotor **60** to each other so that power can be transmitted. The eccentric rotation part **74** includes a connection shaft **76** formed of a coupling rod, a screw rod, or the like known as the related art. Therefore, the eccentric rotation part **74** transmits rotation power generated by operating the driver **80** to the rotor **60**, thereby being capable of causing the rotor **60** to eccentrically rotate.

<<Details of Stator **50**>>

Next, the details of the stator **50** are described. The stator **50** is the sliding member for pumps, which is configured to slide while being in contact with the rotor **60** that is another member along with the operation of the uniaxial eccentric screw pump **20**. As described above, when the rotor **60** is inserted into the through hole **54** of the stator **50**, the fluid conveyance path **56** serving as a flow path of a fluid is formed. Therefore, the stator **50** is arranged so that the inner peripheral surface **52** is exposed to the fluid conveyance path **56**.

The stator **50** is a member containing a resin or a rubber as a main component and has a feature of containing metal powder. It is preferred that the content of the metal powder be adjusted in consideration of the detection accuracy of the detection device to be used for detection of the metal powder, such as a metal locator and an X-ray foreign matter inspection machine, and the decrease in physical properties of the resin or the rubber caused by blending the metal powder. In consideration of the detection accuracy of the

detection device to be used generally and the decrease in physical properties caused by blending the metal powder, it is desired that the blending amount of the metal powder fall within a range of from 10% to 30% in terms of a weight ratio.

The size (average grain diameter) of the metal powder to be blended in the stator **50** may be any size. However, it is preferred that the size of the metal powder be adjusted in consideration of the influence on the detection accuracy of the detection device to be used for detection of the metal powder, such as a metal locator and an X-ray foreign matter inspection machine, and the decrease in physical properties of a resin or a rubber. In consideration of the detection accuracy of the detection device to be used generally and the decrease in physical properties caused by blending the metal powder, the size of the metal powder falls within a range of desirably from 0.1 μm to 300 μm , more desirably from 0.1 μm to 3 μm .

It is only necessary that the metal powder to be contained in the stator **50** be capable of being detected by the detection device for a metal as typified by a metal locator and an X-ray foreign matter inspection machine. Specifically, as the metal powder, for example, one kind of various metal powders such as iron (Fe), copper (Cu), zinc (Zn), cobalt (Co), nickel (Ni), samarium (Sm), and stainless steel (SUS) may be used, or two or more kinds thereof may be used in combination. Further, it is desired that the metal powder to be blended in the stator **50** be selected in consideration of the application 30 of the uniaxial eccentric screw pump **20** and the relationship with a product to be conveyed. Specifically, in the case where the uniaxial eccentric screw pump **20** is used for force-feeding (conveying) food, it is desired that the metal powder be formed of a material, such as iron (Fe), which 35 does not adversely affect a human body even when the metal powder is taken up into the body. In this embodiment, iron oxide (Fe_3O_4) is selected as the metal powder from the viewpoints of less effect on a human body through uptake, and high oxidation resistance and low reaction activity.

<<Detection Device **100**>>

The detection device **100** is a device capable of detecting the presence of the metal powder. As illustrated in FIG. 1, the detection device **100** is arranged partially or entirely in a conveyance path **110** through which a fluid discharged from the uniaxial eccentric screw pump **20** is conveyed. With this, even when a wear substance and a flake of the stator **50** are generated and mixed in the fluid through use of the uniaxial eccentric screw pump **20** in an unintended usage state, the presence/absence of the wear substance can be detected.

As the detection device **100**, a metal detection machine, an X-ray foreign matter detection machine, and the like can be used. In the case of using the metal detection machine, any of a coaxial type, an opposed type, or a permanent 55 magnet type may be used. The metal detection machine has a characteristic that the detection sensitivity is decreased as the content of water and salt in an item to be inspected is larger. Further, the X-ray foreign matter detection device is configured to detect a foreign matter based on the difference in X-ray absorption amount. Hence there is a risk in that the detection sensitivity may be decreased for those having an X-ray absorption amount approximate to that of the metal powder. It is preferred that, as the detection device **100**, a device capable of detecting the metal powder blended in the stator **50** with good accuracy be selected in consideration of the above-mentioned characteristics, the characteristics of a fluid to be conveyed (force-fed) by the uniaxial eccentric

screw pump **20**, the size of a wear substance, which are intended to be at least detected.

<<Control Device **120**>>

The control device **120** is a device configured to determine whether or not a wear substance and a flake of the stator **50** are mixed in a fluid discharged from the uniaxial eccentric screw pump **20** based on the detection results of the detection device **100** described above. The control device **120** determines that a wear substance and the like are mixed in the fluid under the condition that the detection device **100** detects the presence of the metal powder.

<<Operation of Pump Operation State Detection System **10**>>

In what follows, the operation of the pump operation state detection system **10** is described with reference to the flowchart of FIG. 3. In the pump operation state detection system **10**, first, it is confirmed whether or not the uniaxial eccentric screw pump **20** is operated by the control device **120** (step 1). When the uniaxial eccentric screw pump **20** is operated, the control flow proceeds to Step 2, and the detection device **100** detects metal powder in the fluid that is discharged from the uniaxial eccentric screw pump **20** and is passing through the conveyance path **110**.

Then, in Step 3, wear determination is performed based on the detection results of metal powder that are obtained in Step 2. In the wear determination step, various determination conditions may be set, however in this embodiment, whether or not the metal powder is detected as a result of detection of the metal powder in Step 2 is set as the determination condition. Further, when the metal powder is detected, it is determined whether the wear of stator **50** has occurred to such a degree that there is a problem for quality maintenance of the fluid passing through the conveyance path **110**, to thereby determine whether or not an abnormality has occurred. In other words, when the metal powder is not detected in Step 2, degradation in quality of the fluid, which may be caused by the wear of stator **50**, is not assumed, and hence it is determined that no abnormality has occurred.

When it is determined that an abnormality has occurred in Step 3, the control flow proceeds from Step 4 to Step 5, and the operation of the uniaxial eccentric screw pump **20** is stopped. With this, the series of control flows is completed. Meanwhile, when it is determined that no abnormality has occurred in Step 3, the control flow is returned from Step 4 to Step 1, and the control flow of FIG. 3 is continued.

As described further above, the stator **50** of the preferred embodiment is made of a resin or a rubber and contains 10% to 30% of metal powder in terms of a weight ratio. In this way, even if a wear substance of the stator **50** is generated and mixed in the fluid flowing through the fluid conveyance path **56**, due to the use of the uniaxial eccentric screw pump **20** in an unintended usage form, the mixing of the wear substance can be quickly and accurately detected and determined by the detection device **100** and the control device **120**.

In the preferred embodiment, the stator **50** is tapered in an end surface on the discharge side and/or the suction side of the fluid in the stator **50**. Therefore, cracks can be prevented from being formed by the influence of a discharge pressure or a suction pressure on the end surface on the discharge side and/or the suction side of the stator **50**, thereby being capable of minimizing the mixing of a foreign matter such as the wear substance of the stator **50**.

The stator **50**, as described above, has a tubular external appearance, and the through hole **54** having a female screw shape is formed therein. Therefore, the thickness of the resin

or the rubber in each portion is not uniform, but the present invention is not limited thereto. In an alternative embodiment, a stator **150** as illustrated in FIG. 4, which is made of a resin or a rubber having a uniform thickness in each portion and contains metal powder, may be used in place of the stator **50**. In the alternative embodiment, as illustrated in FIG. 4, the stator **150** can be used by the same usage method as that of the stator **50** by holding the stator **150** with an outer casing **152** made of a metal, a resin, or the like.

Further, the stator **50** contains metal powder in a substantially entire region instead of partial regions, but the present invention is not limited thereto. Specifically, it is assumed that the wear substance of the stator **50** is generated in a region on the inner peripheral surface **52** (sliding surface) side on which the stator **50** slides while being in contact with the rotor **60**. Therefore, a stator **250** as illustrated in FIG. 5, which is molded so that the content of metal powder in a vicinity region **252a** (region on a through hole **254** side with respect to the alternate long and two short dashes line in FIG. 5) of the inner peripheral surface **252** is higher than that in another region (outer peripheral region **252b**: region located radially outward with respect to the alternate long and two short dashes line in FIG. 5), may be used in place of the stator **50**.

Specifically, the content of the metal powder may be set to be smaller in the outer peripheral region **252b** than in the vicinity region **252a** in such a manner that the metal powder is contained into a layer forming the vicinity region **252a** of the inner peripheral surface **252**, whereas the metal powder is not contained into the outer peripheral region **252b** located radially outward with respect to the vicinity region **252a**. With such configuration, a foreign matter can be detected also in the stator **250** in the same way as in the case of adopting the stator **50** described above. In addition, the outer peripheral region **252b** can be formed so as to be less liable to be broken. Further, with the configuration of the stator **250**, the vicinity region **252a** and the outer peripheral region **252b** can be made of the same material, or the vicinity region **252a** and the outer peripheral region **252b** can be made of different materials. Note that, in the example illustrated in FIG. 5, the vicinity region **252a** and the outer peripheral region **252b** respectively have a one-layer structure. However, the present invention is not limited thereto, and any one or both of the vicinity region **252a** and the outer peripheral region **252b** may have a multi-layer structure.

In the above-mentioned embodiment, the metal detection machine, the X-ray foreign matter detection machine, and the like are exemplified as examples of the detection device **100**. However, the present invention is not limited thereto, and any device may be used as long as the device can detect the presence of metal powder in the fluid flowing through the conveyance path **110**. Specifically, capture means capable of capturing a substance containing a metal through use of a magnetic force, such as a magnet filter, may be arranged in the conveyance path **110**, and a device capable of detecting the presence of metal powder in the fluid based on the capture state by the capture means may be used as the detection device **100**. More specifically, a device capable of detecting a change in surface magnetic flux density in capture means such as a magnet filter may be arranged as the detection device **100**, and the disturbance of the magnetic field may be detected based on a change in surface magnetic flux density, to thereby detect a foreign matter. Further, a camera such as a CCD camera may be installed in the vicinity of capture means such as the magnet filter, and a device configured to determine the presence/absence of wear powder through the use of an image obtained by photo-

graphing a filter portion may be used as the detection device **100**. Even in the case of using those devices as the detection device **100**, the presence/absence of a foreign matter involved in wear of the stator **50** can be detected in the same way as in the case of using the metal detection machine, the X-ray foreign matter detection machine, and the like.

In the above-mentioned embodiments, the uniaxial eccentric screw pump **20** is exemplified as an example of the pump forming the pump operation state detection system **10**, and the stator **50** is exemplified as an example of the sliding member for the pump. However, the present invention is not limited thereto. That is, for example, in another pump such as a rotary pump, the sliding member for the pump, which is arranged so as to be exposed to the flow path of the fluid in the pump and slides while being in contact with another member along with operation of the pump, may contain metal powder as in the stator **50** described above.

Example 1

In this Example, a test of confirming a change in physical properties due to the configuration in which the metal powder is contained in the sliding member for the pump is conducted. In this Example, a rubber free of metal powder (content: 0%) is prepared as a sample A of Comparative Example. On the other hand, Samples B to D in which the content of iron oxide (Fe_3O_4), which is the metal powder in the rubber, is set to 30% by weight, 20% by weight, and 10% by weight are prepared. Further, the samples A to D are verified for tensile strength, elongation, and tearing strength. The results are summarized in Table 1 and illustrated in FIG. 6.

TABLE 1

	Sample A	Sample B	Sample C	Sample D
Content of iron oxide [%]	0	10	20	30
Tensile strength [MPa]	26.3	24.8	21.3	19.3
Elongation [%]	530	540	550	560
Tearing strength [N/mm]	61.5	59.8	58.9	51.2

As shown in Table 1 and FIG. 6, the following tendency is observed. When the content of the metal powder (iron oxide) increases, the elongation value increases while the tensile strength and tearing strength are decreasing. Assuming the use as the sliding member for the pump such as the stator **50** of the uniaxial eccentric screw pump **20** according to the above-mentioned embodiment, the tensile strength is preferably 19 [MPa] or more, and the tearing strength is preferably 50 [N/mm] or more. From the viewpoints of tensile strength and tearing strength, based on such findings and experimental data of this Example, it has been found that the content of the metal powder in the sliding member for the pump is preferably 10% or more and 30% or less.

Example 2

Results of a detection test are hereinafter described. The detection test is conducted through use of test pieces prepared assuming the wear substance is generated from the rubber sliding member containing the metal powder. Rubber chips being the test pieces to be used in this Example each have a cubic shape, and respectively have a dimension measuring 3 mm, 2 mm, and 1 mm per side, as shown in Table 2. Further, the test piece of each size contains iron oxide (Fe_3O_4) as the metal powder. In this Example, the test pieces are prepared under such configuration that the content

of the metal powder is set to 30% by weight, 20% by weight, and 10% by weight for each size. Further, as a Comparative Example, a rubber chip measuring 3 mm per side, which was free of metal powder, is also prepared.

Further, in this Example, as devices corresponding to the detection device **100**, a metal detection machine (manufactured by Anritsu Industrial Solutions Co., Ltd.: Model No. KD8113AW) and an X-ray foreign matter detection machine (Anritsu Industrial Solutions Co., Ltd.: Model No. KD7405A) are prepared.

In this Example, as workpieces into which the test pieces are mixed, bean paste and mayonnaise, particularly in which the detection accuracy of the above-mentioned metal detection machine and X-ray foreign matter detection machine are assumed to become extremely low, are selected. In this Example, bean paste and mayonnaise are respectively supplied to a container made of polypropylene (PP) having a diameter of 35 mm and a height of 45 mm, and each test piece are mixed therein. The resultant is inspected by the metal detection machine and the X-ray foreign matter detection machine to confirm whether or not the presence of each test piece is detected. Table 2 summarizes the obtained results in each case.

TABLE 2

	Content of iron oxide [%]	Size of iron oxide [mm]	Bean paste		Mayonnaise	
			Metal detection machine	X-ray foreign matter detection machine	Metal detection machine	X-ray foreign matter detection machine
30	30	3	Detected	Not detected	Detected	Detected
		2	Detected	Not detected	Detected	Detected
		1	Detected	Not detected	Not detected	Detected
	20	3	Detected	Not detected	Detected	Detected
		2	Detected	Not detected	Detected	Detected
		1	Detected	Not detected	Not detected	Detected
35	20	3	Detected	Not detected	Detected	Detected
		2	Detected	Not detected	Detected	Not detected
		1	Detected	Not detected	Not detected	Detected
	10	3	Detected	Not detected	Detected	Not detected
		2	Detected	Not detected	Detected	Not detected
		1	Detected	Not detected	Not detected	Not detected
40	10	3	Detected	Not detected	Detected	Not detected
		2	Detected	Not detected	Detected	Not detected
		1	Detected	Not detected	Not detected	Not detected
	0	3	Not detected	Not detected	Not detected	Not detected
		2	Not detected	Not detected	Not detected	Not detected
		1	Not detected	Not detected	Not detected	Not detected

As shown in Table 2, in the case where the bean paste was used as a workpiece, the X-ray foreign matter detection machine was not able to detect any test piece, but the metal detection machine was able to detect all the test pieces. That is, not only the test piece measuring 3 mm per side and containing 30% of iron oxide, but also the test piece measuring 1 mm per side and containing 10% of iron metal, the smallest piece that contained the smallest amount of metal powder, are detected by the metal detection machine.

Meanwhile, in the case where mayonnaise is used as the workpiece, even when the content of the iron oxide in the test piece is any of 10% to 30%, the test pieces were detectable by the metal detection machine as long as the size of the test piece was 2 mm per side or more. Further, it has been found that, in the case of using the X-ray foreign matter detection machine, even when the size of the test piece is as small as about 1 mm, the test pieces are detectable as long as the content of the iron oxide is 20% or more.

11

From the above-mentioned results, it has been found that the test piece assuming a wear substance is detectable even in workpieces such as bean paste and mayonnaise in which the detection accuracy of the metal detection machine and the X-ray foreign matter detection machine are assumed to become extremely low. Furthermore, by selecting the metal detection machine and the X-ray foreign matter detection machine as the detection device 100 in consideration of the kind of workpieces, the minimum size of the wear substance intended to be detected, and the like, the detection accuracy may be optimized.

Embodiments of the present invention are applicable to a general sliding member for pumps that is arranged so as to be exposed to the flow path of a fluid in the pump such as the uniaxial eccentric screw pump or the rotary pump and slides while being in contact with another member along with operation of the pump. Further, the pump operation state detection system of the present invention is suitably applicable to, for example, the case where mixing of the wear substance of the sliding member needs to be avoided as in food and the like.

The invention claimed is:

1. A pump operation state detection system comprising:
a pump having a sliding member which comprises a rubber as a main component, and an amount of metal powder in a range of 10% to 30% by weight ratio;
a detection unit configured to detect a presence of the metal powder contained in the fluid discharged from the pump; and
a control unit configured to perform a determination as to whether or not a wear substance is generated along with wear of the sliding member and is mixed in the fluid discharged from the pump, wherein the determination is performed by the control unit under a condition that the detection unit detects the presence of the metal powder.
2. The pump operation state detection system of claim 1, wherein the sliding member is arranged so as to be exposed to a fluid conveyance path through which the fluid flows.
3. The pump operation state detection system of claim 2, wherein the detection unit is disposed partially or entirely within the fluid conveyance path.

12

4. The pump operation state detection system of claim 1, wherein the sliding member is configured to slide while being in contact with another member of the pump when the pump is operating.

5. The pump operation state detection system of claim 1, wherein the sliding member is used as a stator in a uniaxial eccentric screw pump, said stator having an inner peripheral surface formed into a female screw shape.

10 6. The pump operation state detection system of claim 5, wherein the uniaxial eccentric screw pump further comprises a rotor formed into a male screw shape and configured to receive power to eccentrically rotate within the stator so as to form a fluid conveyance path between the inner peripheral surface of the stator and an outer peripheral wall of the rotor.

7. The pump operation state detection system of claim 1, wherein the resin or the rubber has a uniform thickness.

20 8. The pump operation state detection system of claim 1, wherein the sliding member has an inner peripheral surface configured to slide while being in contact with another member of the pump.

25 9. The pump operation state detection system of claim 8, wherein a content of the metal powder is higher in a vicinity region of the inner peripheral surface than other regions.

10 10. The pump operation state detection system of claim 9, wherein the other regions comprises an outer peripheral region which is located radially outward of the vicinity region.

30 11. The pump operation state detection system of claim 1, wherein the metal powder is selected from the group consisting of iron (Fe), copper (Cu), zinc (Zn), cobalt (Co), nickel (Ni), samarium (Sm), and stainless steel (SUS), or a combination of two or more thereof.

12. The pump operation state detection system of claim 11, wherein the metal powder comprises an iron oxide (Fe_3O_4) if the fluid discharged from the pump contains food.

40 13. The pump operation state detection system of claim 1, wherein a size of the metal powder falls within a range of 0.1 μm to 3 μm .
